UNITED STATES PATENT OFFICE.

RICHARD A. REW, OF POMEROY, WASHINGTON TERRITORY.

HEATING ATTACHMENT FOR COOKING-STOVES.

SPECIFICATION forming part of Letters Patent No. 355,208, dated December 28, 1886.

Application filed July 9, 1885. Serial No. 171,150. (No model.)

To all whom it may concern:

Be it known that I, RICHARD A. REW, a citizen of the United States, residing at Pomeroy, in the county of Garfield, Washington Territory, have invented a new and useful Improvement in Heating Attachments for Cooking-Stoves, of which the following is a description.

Figure 1 is a longitudinal vertical section of a stove provided with my attachments. Fig. 2 is a plan view partly in horizontal section, and Fig. 3 is a vertical transverse section through the line $y y$ of Fig. 1.

The object of my invention is to provide a means for converting cooking-stoves and ranges into hot-air and ventilating stoves, so as to utilize them for the double purpose of cooking and heating the rooms above; and it consists in the peculiar construction of a heating-chamber in combination with the stove, as will be hereinafter more fully described.

In the drawings, A represents the cooking-stove, and B represents the heating-chamber to be attached thereto. This heating-chamber is a rectangular upright inclosure of sheet metal of about the height of the stove, divided into smoke and fire flues and pure hot-air compartments, as follows: C is an upper, and C' a lower, air-space formed within the outer casing by the smoke-drums b and b', and the communicating vertical smoke-pipes b². The smoke-drums b and b' are of less width than the outer casing, (see Fig. 3,) and this allows the air-spaces C and C' to communicate with the space around the pipe b². To the sides of the casing about its middle are attached deflecting shelves C², which extend inwardly toward each other, but leave a space between. The air-space C' has an opening, d, in its bottom, through which it receives fresh air from the outside, and the chamber C at the top has a pipe-connection, d', by which the air which has been heated is delivered to the hot-air flues, which carry the hot air to the points of utilization above.

The stove A has on its rear side the connections a and a', which communicate with the smoke-chamber above and below the oven, which connections are adapted to fit closely the openings in the side of chambers b and b', and the upper one, b, of which chambers communicates with the exit smoke-pipe b³, that

passes up inside the air-pipe d'. At the points a and a' dampers are arranged by which the smoke and products of combustion may be made to pass directly out through chamber b and pipe b³, or be carried down the chamber b' and up through pipes b².

The passage of the smoke and air-currents is as follows: The damper in pipe-connection a being closed, and the one in a' being open, the smoke and products of combustion pass into the chamber b' up through flues b² to chamber b, and thence out b³ to the chimney. These chambers b and b' and b² serve to heat the pure air which is brought into external contact with them as follows: This pure air enters opening d in the bottom of chamber C, and passes thence around the sides of the smoke-chamber p', then is diverted across the lower portion of flues b² by the shelves C², and passing up between them crosses the flues b² at the top in an outward direction, and thence passes up on the outside of chamber b to the hot-chamber C, and thence through pipe d' to the point of utilization. The fresh air admitted through opening d at the bottom is made to travel a winding course over the fire-heated surfaces and becomes thereby thoroughly heated.

From the cool-air chamber C a pipe, D, with damper D², extends to the front of the stove, and ascending to the fire-pot communicates with a space at the end of the fire-pot opposite the door, as shown at A', Fig. 2, and which space communicates with a space, A², between the fire-back and oven, and from which the heated air passes out through a pipe, A³, into the room.

D' is a dip-pipe of trap shape, which descends from the draft-space of the stove nearly to the floor, and which supplies air for combustion, taking it from the lowest stratum in the room, where the air is cold and impure. This pipe D' has a damper, D², in the same to regulate the draft. The object of the trap or bend in this trap is to catch live coals that may drop down this pipe, and prevent the same from falling down upon and setting fire to the floor.

I do not in this application claim, broadly, the trap-shaped pipe for supplying air to the combustion-chamber, nor yet the particular construction as shown for connecting the pipe with such chamber, as such invention is

claimed in a separate application for patent filed by me on or about November 23, 1886, Serial No. 219,701.

Having thus described my invention, what I claim as new is—

1. The combination of the stove having rear vertical smoke-flue with connections a and a' at top and bottom of same and the heating-chamber B , consisting of outer case with lower space, C' , and inlet d , upper space, C , and outlet d' , the smoke-drums b and b' , communicating, respectively, with the connections a and

a' of the stove, and connecting smoke-pipes b' , arranged within the outer case, substantially as and for the purpose described.

2. The stove having passages A^2 in rear and A' at the end of the fire-chamber, and inlet-pipe D , and outlet A^3 , in combination with the casing B , having air-chamber C' , and inlet d , substantially as shown and described.

RICHARD A. REW.
